UNITED STATES PATENT OFFICE

WILLIAM M. STOCKMAN, OF CHICAGO, ILLINOIS

PICTURE FRAME

Application filed March 15, 1932. Serial No. 598,991.

This invention relates to frames of the type adapted to hold a picture or the like removably, and may be used either as a wall frame or a desk frame, and more particularly to a novel and improved method for constructing the same from a single sheet of metal, such for example as brass or the like.

In the construction of frames of this character heretofore used, the frame is built up from a number of sections which are rigidly secured to each other in any suitable and well known manner, such for example as welding or the like, with the result that certain prominent seams will be present on the frame, which seams tend to mar the attractive appearance of the frame. In addition to that, the construction of a frame in this manner is comparatively expensive, as it involves considerable labor as well as a considerable waste in material.

The main object of this invention is to overcome the above difficulties and disadvantages by constructing a frame from a single sheet of metal, the complete operation being performed by suitable dies whereby the necessity for any fastening means or welding is entirely eliminated.

The invention contemplates certain novel and improved steps in the formation of a picture frame from a single piece of sheet metal, with the result that a highly attractive frame is produced, which will be both easy and economical to manufacture along lines convenient for low cost production, while at the same time being highly efficient for carrying out the purposes for which it is designed.

A further object of this invention is the novel and improved method for constructing a picture frame from a single sheet of metal, wherein the material wasted in the construction of the same is reduced to a minimum.

According to the invention, the frame is formed from a single blank of sheet metal, such as brass or the like, by suitable dies. This blank of sheet metal after having been cut to the desired size is notched at the corners and provided in the central portion thereof with a picture opening of the desired shape and size. The next step in my

improved method is to draw up the sides of the blank to form upwardly extending flanges, the free edges of some of said flanges being then turned at right angles to form guide rails. The notches provided in the blank before the drawing up of the sides of the same will permit the ready turning inwardly of said side flanges without there being any overlapping of material at the corners. The complete operation of the formation of the frame is thus accomplished by suitable dies, one of which will blank and notch the sheet of metal, and the other of which will draw out the same to form the side flanges and guide rails.

By constructing a frame with this improved method it should be readily apparent that not only is there eliminated the necessity for securing the different sections of the frame to each other, but also a considerable saving in both labor and material is accomplished, with the result that a very attractive and durable frame is produced at a very low cost.

With the foregoing and other objects in view, which will appear as the description proceeds, the invention consists in the novel and improved steps in the method of constructing a picture frame, certain novel features of construction, arrangement and combination of parts hereinafter more fully described, illustrated in the accompanying drawing, and particularly pointed out in the appended claim, it being understood that various changes in the form, proportion, size and minor details of the structure and in the steps of the method may be made without departing from the spirit or sacrificing any of the advantages of the invention.

For the purpose of facilitating an understanding of my invention I have illustrated in the accompanying drawing a preferred embodiment thereof, from an inspection of which, when considered in connection with the following description, my invention, its mode of construction and assembly, and many of its advantages should be readily understood and appreciated.

Referring to the drawing in which the same characters of reference are employed

to indicate corresponding or similar parts throughout the several figures of the drawing:

5 Figure 1 is a top plan view of a blank of sheet metal which has been notched at the corners thereof and from which my improved frame is to be formed;

10 Figure 2 is a view in perspective of the blank shown in Figure 1 after the same had been drawn up at the sides to form the upstanding marginal flanges;

15 Figure 3 is a view in perspective of the completed frame formed from the blank shown in Figure 1; and

20 Figure 4 is a longitudinal sectional view through the frame having a picture mounted therein in fully assembled position.

25 In the method contemplated of forming the frame, a blank 10 of sheet metal, such for example as brass or the like, is cut out at its central portion to form the picture opening 11, said picture opening being of any desired shape, such for example as rectangular, circular, elliptical, or the like. 30 and of course, of any desired size. It should be apparent that the metal cut out of the blank 10 to form the opening 11 may be utilized as a blank for the formation of another picture frame of reduced size in the manner to be hereinafter more fully described.

35 At the same time that the picture opening 11 is provided the upper and lower corners of the blank may be notched as indicated at 12 and 13, the shape of the notches provided at 12 at the upper end of the blank being different from that provided at 13 at the lower end thereof in order to produce the construction illustrated in Figure 2 after 40 the marginal edges of the blank have been drawn up, which is to be done in the next step of my improved method.

45 Upon the completion of the notching of the blank, the side edges thereof are then drawn up by a suitable die to form the upstanding side flanges 14 and 15, the upstanding top flange 16 and the upstanding bottom flange 17. By reference to Figure 2, it will be noted that the flange 17 is of a 50 height which is considerably less than the height of the flanges 14 and 15. The reason for that will be apparent from an inspection of Figure 3 of the drawing.

55 The next step in the formation of the frame is the turning inwardly of the free edges of the top flanges 14, 15 and 16 to form the guide rails 18 and 19 and the top rail 20. By providing the notches 12 it will be apparent that the turning down of 60 said flanges 18, 19 and 20 will not be interfered with by the overlapping of the said flanges at their meeting edges.

65 The completed frame will comprise the rectangular front framing section 21, upon the outer marginal edges of which have been

formed the rearwardly extending side flanges 14 and 15, top flange 16 and bottom flange 17, the said side flanges 14 and 15 terminating in the inwardly turned guide rails 18 and 19 respectively. The top flange 16 also terminates in the inwardly turned flange 20.

70 The front of the frame will present a uniform surface which is not marred by any welding seams or the like, and may be readily decorated in any approved manner, such for example as by etching or the like, to produce the desired ornamental appearance thereon. Obviously, the manner in which the frame is decorated is quite immaterial to the present invention, and various types of 75 plans or ornate designs may be used for this purpose.

75 In its operative position, a back 30 is held in place by the flanges 18, 19 and 20, preferably by frictional contact with the inner faces of said flanges, said back serving to force the picture 31 and the glass 32 firmly against the inner face of the framing section 21. In mounting the picture, the glass 32 is first 80 inserted in place by sliding the same between the upper edge of the bottom flange 17 and the inner faces of the flanges 18 and 19. The picture 31 is secured to the back of said glass in any suitable and well known manner so 85 that the same may be readily viewed through the opening 11 in the frame. The back 30 is preferably covered with felt, velvet or similar soft cushioning fabric, and is of a thickness corresponding to the distance between the back of the picture 31 and the inner faces of the guide rails 18 and 19. It will be 90 noted that the flange 17 is provided with no 95 guide rail, so that the back 30 may be readily slid into position under the guide rails 18 and 19 from the lower end of the frame.

100 The back 30 may carry the usual easel (not shown), or the same may be provided with a pair of eyes or other hangers (not shown) for receiving the ends of a picture wire or the like, whereby the assembled frame may be 105 readily supported either in a standing or hanging position. When in assembled position it will be noted that the friction between the covering of the back 30 and rails 18 and 110 19 is sufficient to normally prevent the back from dropping out when the frame is lifted from its support, whereas the upstanding flange 17 forms a support for the lower edge of the glass when the assembled frame is 115 either in a hanging or standing position.

120 It will, of course, be understood that where frames of different shapes are desired, the blank of sheet metal will be correspondingly varied. While I have shown one way in 125 which the invention may be carried out, it will be readily understood that the principles of the invention may be utilized in other ways and through other forms of mechanism than those suggested herein, the selection of a 130

specific embodiment being determined more particularly by the exigencies of use or the particular wishes of the user, and I reserve the right to make all such changes in and adaptations of the construction of my invention as fairly fall within the scope of the accompanying claim when broadly construed.

What I claim and desire to secure by Letters Patent of the United States is:—

- 10 A picture frame having a framing section provided with a picture opening centrally disposed therein, the side, top and bottom edges of said framing section being drawn up to form marginal upstanding flanges integral with each other and with said framing section, one of said flanges being of a height substantially equal to one-half of the remaining of said flanges, the two upper corner portions of said upstanding flanges
- 15 being cut away to a point substantially half-way to the bottom of said flanges, the free edges of the top and side flanges being bent inwardly to form inwardly extending flanges to provide guide rails for the insertion of a
- 20 back for holding a picture and glass in assembled position within the frame.
- 25

In testimony whereof, I affix my signature.

WILLIAM M. STOCKMAN.
